UNITED STATES PATENT OFFICE.

WILLIAM H. VOSS, OF DAVENPORT, IOWA.

WRINGER.

1,344,835.

Specification of Letters Patent. Patented June 29, 1920.

Application filed May 11, 1917. Serial No. 167,856.

To all whom it may concern:

Be it known that I, WILLIAM H. Voss, a citizen of the United States, residing at Davenport, in the county of Scott and State 5 of Iowa, have invented certain new and useful Improvements in Wringers, of which the following is the specification.

My invention relates to improvements in wringing machines in which a new and useful arrangement of safety guard and table, respectively, is embodied, and more particularly to that combination, construction and arrangement of parts as will result in the quick, efficacious and simple adjustment and 5 operation of said guard and table.

One of the objects of this invention is to provide a table so attached to the wringer frame that when the clothes are pushed along its top by the operator they will feed 0 into the rolls with the least possible effort, and so constructed that should the clothes wrap around the rolls, the table will automatically rise and move away from said rolls, and which table may be swung back 5 so that the rolls may be readily cleaned should they become soiled.

A further object of this invention is to so construct the table that no sharp or rough edges will be presented to the clothes passing 0 thereover, and at the same time prevent the clothes from sliding off the table when they are boiling hot and difficult for the operator to handle.

A still further object of the invention is 5 to provide a guard for the upper roll of such nature that it will not interfere with the clothes passing over the rolls, and at the same time will rise with the upper roll when such movement is caused by an extra 0 thickness of clothes passing between the rolls.

Another object of the invention is to so arrange the guard for the upper roll that it will be capable of both a vertical translation and an outwardly swinging movement, both of which movements will be accomplished in an even and smooth manner, thus enabling the guard to be readily lifted or 5 swung away when it becomes necessary to clean the rolls, or when the clothes become entangled therein.

Another object of the invention is to provide such a guard that there will be no necessity of pushing the clothes any considerable distance beyond the guard before 5 coming in contact with the rolls, thus adding considerably to the efficiency of the guard,

and at the same time preventing the operator from coming in contact with the dangerous, moving upper roll.

60

Other objects and advantages will appear as the following description proceeds, it being understood that although I have illustrated and described a preferred embodiment of my invention, there are various changes and modifications that may be made without departing from the spirit of my invention, except as limited by the appended claims.

70

In the drawings:—
Figure 1 is a side elevation of a wringer embodying my invention.

Fig. 2 is a top plan view of the same.

Fig. 3 is a vertical transverse section taken on line 3—3 of Fig. 1 and looking in the 75 direction of the arrows.

Fig. 4 is a vertical transverse section through the rolls and upper guard members, and showing one of the guard members partially raised.

80

Fig. 5 is a fragmentary perspective view of the upper portion of the roll-frame to which the upper guard members are pivoted.

Referring to the several views of the drawings in which similar numerals refer 85 to similar parts, 1 designates the supporting legs which are provided with rectangularly meeting faces 2 and 3 at their lower end so arranged that the wringer may be readily secured by means of suitable bolts passing 90 through the slots 4 to any desired supporting structure.

95

In the upper part of the frame work are secured in the roll-frames 24, 24, the usual rolls 5 and 6, which may be driven by means of any suitable power. The pressure between the rolls may be readily adjusted and regulated by means of the wing nuts 7, which by being raised or lowered increase or decrease the amount of compression in the spiral springs 8, which in turn transmit this tightening or loosening effect to the rolls through the medium of the bar 9, which presses down upon the upper roll by virtue of the journal 10 formed upon the end of 105 said bar 9. A drip pan or chute 11 is pivotally mounted upon the supporting legs 1 by means of the pivot 35, and has attached to the under side thereof the gripping device 11' which by frictional engagement with the rod 36, will hold the drip pan 11 in tilted position for use from either side of the wringer as desired. The drip pan 11 is constructed after the manner of an open ended 110

chute for the purpose of returning the excess water to the tub, washing machine, or other device upon which the wringer may be mounted.

- 5 Located upon one or both sides of the wringer and adjacent the lower roll thereof is a table designated generally by A. This table comprises a tray 12, which is pivotally mounted between the outer end of the side arms 13 by means of a rod 32. The side arms are attached to the cross arm 17, which in turn is attached to the body of the wringer. The rear edge of the tray 12 is set into or otherwise attached to a strip of wood 14, and has a series of holes 15 located directly in front of said wooden strip 14, the purpose of these holes being to permit the escape of any water which would otherwise be collected in front of the wooden strip 14.
- 10 The front edge of the tray is spaced slightly from the lower roll, and is provided with a down turned bead or flange 16, and rests, slightly in the rear of said flange, on the cross bar 17, attached to the body of the
- 15 20 25 wringer.

As is apparent, the construction and arrangement of this table is such as to permit the clothes when pushed along its top to feed into the rolls with the least possible effort, and also by virtue of its being hinged at its outer end, will, in case the clothes should become wrapped around the lower roll, automatically be raised by the clothes coming in contact from the underside with the flange 16, thus swinging the tray 12 away from said rolls; and should it be desired this table may readily be swung on its pivot away from said rolls in order that they may be readily cleaned should they become soiled. The wooden strip 14 is so placed that the clothes passing onto the table will not drag over the metal edge of the tray and this strip further prevents the clothes from sliding off of the table when they are boiling hot and difficult to handle. The tray 12 is preferably made of metal so as to prevent warping, and also to render it possible to place the edge of the tray nearer the rolls than would be the case if wood were used instead.

In combination with the table hereinbefore described, I have provided an upper guard represented generally by B, which consists of a guard bar 18 of suitable material extending across and slightly spaced from the upper roll in appropriate position to prevent the operator from coming in contact with the dangerous upper roll. Suitably secured at each end of this guard bar 18 is a metal strip or hanger 19, the upper portion of which is turned at right angles to the lower portion to form the ear 20, which carries a perforation 21. Pivotally secured to the ear 20 is the link 22, which is provided at its inner end with the

perforation 23, and at its outer end with a perforation to register with the perforation 21.

In Fig. 5 is illustrated the upper portion of one of the slotted roll-frames 24, upon which is formed as shown the ear 25, which is provided with the apertures 26, 27, and the lugs 28, 29. The links 22 (one at each side) are preferably formed by a suitable rectangular bend at each end of a metal bar 30, which bar is of such length as to fit for a snug turning movement between the ears 25 located at the opposite ends of the upper portion of the wringer. This fit may, if desired, be accompanied by sufficient friction to hold the guard suspended in whatever position it may be placed. By means of this bar 30, when one end of the guard bar 18 is raised, the other end will rise with it, thus insuring both ends of the guard bar working in unison. In assembling, the links 22 which are carried upon each end of the bar 30, the holes 23 and 26 are brought into registering relation, and suitable pivot pins passed therethrough. The hole 21 and the hole in the outer end of the link 22 are also brought into registry, and the link 22 and the ear 20 secured for pivotal movement in a similar manner.

The hanger 19 is provided at its lower end as shown in Fig. 1 with the ear or projection 31, whose function is to bear against the roll-frame 24, and thus hold the guard bar 18 when in operative position, a predetermined distance away from the upper roll 5.

It will be noted in Figs. 1 and 5 that the roll-frame 24 is provided near its upper portion with an apertured lug 37, which lug is rigidly secured by means of a suitable bolt to the journal box 10 of the upper roll. From this construction it is apparent that as the upper roll moves up and down, the journal box 10, the roll-frame 24, and the guard member 18 will consequently move up and down therewith, thus causing the guard bar 18 to have an up and down movement in unison with the up and down movement of the upper roll 5.

When the guard bar 18 is in its lowest position, in other words, its operative position, the lower edge of the link 22 will rest upon the lug 28, thus holding the guard steady and from further downward movement. Should the clothes become tangled, or should it become necessary to clean the rolls, the upper guard may be readily lifted vertically or swung outwardly, and at the same time the table A may be turned on its axis 32 back from the lower roll, and both rolls be thus made readily and quickly accessible. After the rolls have been cleaned, or the clothes untangled, the table and guard are by a simple movement or two of the hand easily and quickly thrown again 130

into operative position, thus completely eliminating any tedious manipulation or difficult adjustment of the guard and table.

Such parts as the drip pan 11 and the tray 12 will preferably be formed of sheet metal, while the guard bar 18, the cross bar 17, and the strip 14 will preferably be made of wood. However, the use of other materials for these parts, if desired, would not 10 depart from the spirit of my invention.

From the foregoing description, it is apparent that I have provided in combination a new and useful table and guard, which table and guard may be quickly thrown into 15 adjusted position for cleaning the rolls and other parts, and which guard when in operative position will effectively prevent the operator from coming in contact with the upper roll, will not interfere with the clothes 20 passing over the table and into the roll, and which tray and guard, especially the latter, are capable of an even and smooth adjustment, thus eliminating all jerky, uneven and 25 unsteady movements which are so undesirable in the quick adjustment of these parts.

Having now described my invention, I claim:—

1. In wringing apparatus, a body portion, a pair of rolls, a guard bar adjacent one of said rolls, means connecting said bar to said body portion for permitting both vertical rectilinear and outwardly swinging adjustment of said bar with relation to said 30 body portion, said means retaining said bar in whatever vertical rectilinear position it may be placed.

2. In wringing apparatus, a body portion, a pair of rolls, a guard bar adjacent one of 40 said rolls, a hanger on said bar, a link pivoted to said bar and said body portion to permit both a vertical rectilinear and outwardly swinging movement of said bar, the joints between the link, the bar and the 45 body portion being sufficiently tight to hold the bar in whatever vertical rectilinear position it may be placed.

3. In a wringer, a roll-frame, an ear on 50 said frame, a lug on said ear, a guard bar, a hanger secured to said guard bar, a link pivoted at one end to said hanger and at the other to said ear, the lower edge of said link resting on said lug when said guard bar is in operative position.

4. In a wringer, a pair of roll-frames, an ear on each of said frames, a lug on each of 55 said ears, a guard bar, a hanger secured to each end of said guard bar, a link for each of said hangers, said links being pivoted at one end to said hanger and at the other end to said ear, said links being rigidly connected together by a bar and the lower edges of said links resting on said lugs to hold the guard bar in operative position.

5. In a wringer, a pair of side arms, a 65 table pivoted near its outer edge to the outer portions of said side arms, the inner edge of said table being supported adjacent the lower roll of said wringer when in operative position.

6. In a wringer, outwardly extending side arms, a table pivoted near its outer edge to said arms and having its inner edge when in operative position supported adjacent the lower roll of said wringer, and the outer edge 70 of said table being provided with a wooden strip to prevent the clothes sliding off therefrom backwardly.

7. In a wringer, outwardly extending side arms, a table pivoted to said side arms, said 80 table comprising a sheet metal tray having a rounded strip of wood fitted over the rear edge thereof, and said tray being provided immediately in front of said wooden strip with a series of perforations to permit the 85 drainage of water from said table.

8. In a wringer a frame having a pair of rolls, a journal box on each end of the upper roll, a guard bar, a hanger secured to each end of said bar, a pair of links each 90 pivotally connected at one end to one of said hangers and at the opposite end to said journal boxes respectively, and means connecting said links to cause them to move in unison whereby both ends of said bar will 95 move also in unison.

9. In a wringer a frame having a pair of rolls, a journal box on each end of the upper roll and mounted to move up and down therewith, a link pivotally connected 100 to each of said boxes, a hanger pivoted to each of said links, a guard bar carried by said hangers whereby said bar may have either rectilinear movement in a vertical plane or may swing in the arc of a circle, 105 there being sufficient friction in the pivotal connection of the link with the box to hold the bar in adjusted position in said vertical plane.

10. In a wringer a body portion, a pair 110 of rolls, a guard bar for said rolls, a hanger on each end of said bar, a pair of links each pivotally connected at one end to one of said hangers and at the other end to said body portion, the length of said links being small compared with the length of said 115 hangers, and means to normally hold said links in a horizontal position whereby said bar may have either rectilinear movement in a vertical plane or swinging movement. 120

In witness whereof, I hereunto subscribe my name to this specification in the presence of two witnesses.

WILLIAM H. VOSS.
